193.303.

FIG. 1 is a perspective view of a devotional desk showing my design.

FIG. 2 is an enlarged side elevational view of the devotional desk shown in FIG. 1.

FIG. 3 is an enlarged top plan view of the devotional desk shown in FIG. 1.

FIG. 4 is an enlarged front elevational view of the devotional desk shown in FIG. 1.

FIG. 5 is an enlarged rear elevational view of the devotional desk shown in FIG. 1.

The broken line showing of a cushion in FIG. 2 and FIG. 4 is for illustrative purposes only.

I claim:

The ornamental design for a devotional desk substantially as shown and described.
